E. BERG

ELECTRIC BOILER

Filed Sept. 13, 1922

Inventor:
Eskil Berg;
by *Alexander S. Smith*
His Attorney.

UNITED STATES PATENT OFFICE.

ESKIL BERG, OF SCHENECTADY, NEW YORK, ASSIGNEE TO GENERAL ELECTRIC COMPANY, A CORPORATION OF NEW YORK.

ELECTRIC BOILER.

Application filed September 18, 1923. Serial No. 328,071.

To all whom it may concern:

Be it known that I, ESKIL BERG, a citizen of the United States, residing at Schenectady, in the county of Schenectady, 5 State of New York, have invented certain new and useful Improvements in Electric Boilers, of which the following is a specification.

The present invention relates to electric 10 boilers of the type in which one or more electrodes dip into liquid contained in a casing and generate vapor by the passage of electric current through the liquid. Usually the liquid is water and the vapor generated is steam but my invention is well 15 adapted for use with other liquids as is pointed out more fully hereinafter.

In connection with electric boilers the 20 condition is sometimes met with where it is not practical to apply the electric current directly to the liquid to be vaporized. Instances of this are as follows:

If the source of electrical energy available and to be used for generating vapor 25 is of low voltage, it may be that the liquid (for example, pure water) offers such high resistance to the passage of current as to seriously limit the capacity of the boiler; or, on the other hand, if the source of electrical energy available is of high voltage 30 while the liquid to be vaporized is of low resistance, (for example, pure water) it may be very difficult or impractical to provide a boiler which will offer sufficient resistance 35 between the electrodes. An electric boiler generates saturated steam and if dry steam or superheated steam is required it cannot be directly generated by the electrodes. Again it may be desired to generate vapor 40 from a liquid to which it is not practical to apply the current directly because of the fact that passage of current through the liquid adversely affects it due to electrolysis or other cause.

45 The object of my invention is to provide an electric boiler which will take care of any of the above or similar conditions in a practical manner and for a consideration of what I believe to be novel and my invention, 50 attention is directed to the accompanying description and the claims appended thereto.

According to my invention, I provide a 55 boiler containing the electrodes and use in it a liquid suited to the voltage available and I then utilize the vapor generated in

this boiler in a second boiler which contains the liquid to be vaporized. The vapor from the first boiler serves to generate vapor in the second boiler and is itself condensed and returned to the first boiler for use again. 60

In the drawing, the figure is a diagrammatic view of boiler apparatus embodying my invention, the boilers being shown in section. 65

Referring to the drawing, 5 indicates a boiler shell of suitable boiler construction into which project one or more electrodes 6, two being shown in the present instance. As is well understood, the numbers of electrodes depend among other things, on the character of the current supplied. The arrangement shown is to be taken as typical of any suitable type of electric boiler. Located adjacent boiler 5 is a second boiler 7 having a liquid feed pipe 8 and a vapor discharge pipe 9. In boiler 7 is a coil or pipe structure 10 connected at one end by pipe 11 to the top of boiler 5 and at the other by pipe 12 to the bottom of boiler 5. 70 There is thus formed a closed circuit for the flow of fluid from boiler 5 through pipe 11 to coil or pipe structure 10, thence through coil or pipe structure 10 back to boiler 5 by way of pipe 12. The flow of 75 fluid from boiler 7 back to boiler 5 may be by gravity providing boiler 7 is placed at a higher level than boiler 5 or a pump as indicated at 13 may be inserted in pipe 12 either to assist the flow by gravity or to itself transfer the fluid from boiler 7 to boiler 5. Connected to boiler 5 is an 80 inlet pipe 14 containing a valve 15 through which liquid may be supplied to boiler 5. In the bottoms of boilers 5 and 7 are blow-off valves 16 and 17 for drawing off liquid. 85

In operation electric boiler 5 is filled to a suitable level with the liquid to be used therein and boiler 7 is supplied with the liquid to be vaporized, the vapor of which 90 is to be used for the required or intended purpose. The electrical input to boiler 5 may be regulated in any suitable way. For example, it may be regulated by varying the level of the liquid in the boiler, or by 95 adjusting the electrodes to vary the depth to which they are submerged in the water. The vapor generated in boiler 5 flows through the heating coils or pipe structure 10 in boiler 7 and heats the liquid therein 100

thus vaporizing it. The vapors are then carried off through pipe 9 to the point where they are to be used. The vapors from boiler 5 in passing through heating coil 10 are condensed and returned to boiler 5. There is thus established in connection with boiler 5 a closed heating system. This makes it a very simple matter to regulate boiler 5 because the same liquid is boiled 10 continuously and its makeup or electrical resistance does not change.

The boilers may be run at various temperatures and pressures to meet the requirements of particular cases. Usually it will 15 be desirable to run boiler 5 at a substantially higher pressure and temperature than boiler 7, so there will be rapid interchange of heat between the two and the size of the coil 10 kept within practical limits.

20 Some specific examples of applications of my invention are as follows:

A condition may be met with where low voltage current is available for use in operating a boiler and the liquid to be vaporized, 25 for example, water is quite pure so that it has a high resistance. In such a case the boiler 5 may be supplied with a water solution of calcium chloride, sodium hydroxide or similar substance which will give a solution having a relatively low electrical resistance. The liquid of high resistance to be boiled, for example water, is then supplied to boiler 7 and is vaporized by the vapors from boiler 5 flowing through the heating 30 coil or pipe structure 10.

Again, a condition may be met with where high voltage current is available and the liquid to be vaporized has a relatively low resistance, for example impure water. In 40 this case a liquid having a high electrical resistance, for example pure water may be used in the boiler 5 and a liquid having a low resistance, for example impure water, vaporized in boiler 7.

45 In other applications of my invention, it will be clear that with either high resistance liquid or low resistance liquid used in the boiler 5, any desired liquid may be vaporized in the boiler 7.

50 I may, furthermore, use a substance in boiler 5 which has a high boiling point and utilize the vapors therefrom to boil a substance of lower boiling point in boiler 7.

In this case boiler 5 may be operated at atmospheric pressure if desired while boiler 55 7 may be a high pressure boiler.

If it is desired to superheat the vapors generated in boiler 7, the level of the liquid therein may be kept such that the upper portion of tube structure 10 serves as a superheater. In this case the upper portion may be specially shaped if found desirable.

In accordance with the provisions of the patent statutes, I have described the principle of operation of my invention together 65 with the apparatus which I now consider to represent the best embodiment thereof, but I desire to have it understood that the apparatus shown is only illustrative and that the invention may be carried out by other 70 means.

What I claim as new and desire to secure by Letters Patent of the United States, is:

1. In combination, an electric boiler, a second boiler, and a pipe structure in the 75 second boiler connected to the electric boiler.

2. In combination, an electric boiler adapted to contain a liquid and having electrodes which project into it, a second boiler, 80 a heating coil in the second boiler, and conduits connecting the ends of the heating coil to the electric boiler.

3. A boiler structure comprising an electric boiler having electrodes which dip into the liquid to be vaporized in the electric boiler, characterized by the fact that the vapor generated in the electric boiler is used as a heating means for vaporizing liquid in a second boiler after which it is condensed 90 and returned to the electric boiler.

4. A boiler structure comprising an electric boiler having electrodes which dip into the liquid to be vaporized in the electric boiler, a second boiler containing a fluid to 95 be heated and having an inlet and an outlet for said fluid, and means located in the second boiler in thermal contact with the fluid therein and connected with the electric boiler to form therewith a closed circulating 100 system for the liquid vaporized in said electric boiler.

In witness whereof, I have hereunto set my hand this 12th day of September, 1922.

ESKIL BERG.
